US0D1070602S

(12) **United States Design Patent** (10) **Patent No.:** **US D1,070,602 S**
(45) **Date of Patent:** **** Apr. 15, 2025**

(54) **PACKAGING BOTTLE**

(71) Applicant: **SUNTORY HOLDINGS LIMITED**,
Osaka (JP)

(72) Inventors: **Tatsuki Kado**, Tokyo (JP); **Yoshihiro Saito**, Tokyo (JP); **Yuichi Osumi**,
Osaka (JP); **Daisuke Ogino**, Tokyo (JP)

(73) Assignee: **SUNTORY HOLDINGS LIMITED**,
Osaka (JP)

(**) Term: **15 Years**

(21) Appl. No.: **35/518,278**

(22) Filed: **May 24, 2023**

(80) **Hague Agreement Data**

Int. Filing Date: **May 24, 2023**
Int. Reg. No.: **DM/231107**
Int. Reg. Date: **May 24, 2023**
Int. Reg. Pub. Date: **Sep. 8, 2023**

(57) **CLAIM**

The ornamental design for a packaging bottle as shown and described.

DESCRIPTION

1. Packaging bottle

1.1: Front

1.2: Back

1.3: Left

1.4: Right

1.5: Top

1.6: Bottom

1.7: Perspective

1.8: Cross sectional

1.9: Cross sectional

1.10: Cross sectional

1.1 front view; 1.2 back view; 1.3 left side view; 1.4 right side view; 1.5 top view; 1.6 bottom view; 1.7 perspective view; 1.8 cross-sectional view taken on line A-A of the front view 1.1; 1.9 cross-sectional view taken on line B-B of the front view 1.1; 1.10 cross-sectional view taken on line C-C of the front view 1.1.

The broken lines depict portions of the packaging bottle that form no part of the claimed design.

1 Claim, 10 Drawing Sheets
